UNITED STATES PATENT OFFICE

130,969

DESIGN FOR A DRESS

Max Frumkin, New York, N. Y.

Application December 10, 1941, Serial No. 104,552

Term of patent 3½ years

To all whom it may concern:

Be it known that I, Max Frumkin, a citizen of the United States and a resident of the city of New York, in the county of Kings and State of New York, have invented a new, original, and ornamental Design for a Dress, of which the following is a specification, reference being had to the accompanying drawing, forming a part thereof.

Fig. 2 is a rear view of the dress shown in Fig. 1.

Fig. 3 is a front view of the dress shown in Fig. 1 with the detachable gilet removed.

I claim:

The ornamental design for a dress, substantially as shown.

MAX FRUMKIN.
